[57]

ABSTRACT

A mechanism for the transportation of an information carrier in which the information carrier is unwound from a supply spool onto a take-up spool, the latter being driven by a hydraulic motor coupled in non-slip driving relation therewith. A metering valve is connected to the hydraulic motor for controlling the flow of a working liquid thereto from a pressure source and the valve is controlled by a gauge which responds to the diameter of the information carrier on the take-up reel so that the rate of flow of working liquid to the hydraulic motor is related to the amount of information carrier on the take-up reel whereby the information carrier is driven at a constant linear speed. The mechanism is entirely enclosed within a hermetic housing which is filled with a liquid.

FIG. 1

FIG. 2

MECHANISM FOR TRANSPORTATION OF AN INFORMATION CARRIER

The present invention relates to information handling means, and, more particularly, to information recording apparatus, for instance, for recording information on a magnetic tape or a magnetic wire, incorporated into various systems of automatic inspection, registration, control and the like. Still more precisely, the present invention relates to mechanisms for transportation of an information carrier.

The invention can be employed, for example, for transportation of magnetic tape, magnetic wire, etc. in an apparatus for magnetic recording of information, belonging to a system of registration of the flight data of an aircraft, or else to registration or control systems employed by railways, ships, traffic control networks; it may also be employed in the program control apparatus of metal working machine tools and other machines, production lines, conveyors, etc.; in the automatic system of production control in various industries; in computers and like machines, etc.

The present invention, however, may be used to an utmost advantage in association with an apparatus incorporating a source of hydraulic power, i.e. of a liquid under pressure, as for instance, in an aircraft or some other vehicle, a machine tool, etc. Additionally, a mechanism embodying the present invention is well adapted to use metal magnetic tapes or bands as the information carrier.

In mechanisms for transportation of an information carrier, the most important tasks that present certain difficulties are to combine a simple enough structure of the mechanism with an increased reliability thereof, particularly, under trying physical and climatic conditions, to ensure a constant transportation speed of the information carrier and its uniform tensioning and to prolong the operational life of the mechanism.

The known mechanisms are usually not adapted to be operated with metal information carriers of magnetic records, notwithstanding the fact that these information carriers have a number of advantages.

There are known mechanisms wherein a constant speed of transportation of an information carrier is provided by a driving shaft rotating at a fixed speed and operatively associated with said information carrier. However, the presence in these mechanisms of the driving shaft associated with the information carrier reduces the reliability of their performance. This poor reliability becomes particularly pronounced under trying climatic conditions, e.g. when the humidity is very high, since under these conditions the information carrier might slip in relation to the driving shaft.

It is known that a magnetic recording is made on an information carrier by magnetic recording heads, which fact, on account of the dry friction between the heads and the information carrier, reduces the operational life of the entire recording apparatus, particularly in cases when it is highly desirable to use metal information carriers.

There are known mechanisms wherein transportation of an information carrier is effected by simply winding the information carrier onto the take-up spool.

However, in these mechanisms the linear speed of the transportation of the information carrier permanently varies, following the varying diameter of the winding of the information carrier on the spool, which imposes se-

rious limitations as to the scope of the practical uses of such mechanisms.

For example, in a mechanism for transportation of an information carrier, employed in the magnetic recording apparatus for aircraft, Model MR-31D and other models (see the catalogue of the "SES" Company, the "Dala-Saor" Chicago Division), in order to improve the stability of the speed of transportation of the information carrier, there are employed a flywheel mounted on the driving shaft adapted to drive the information carrier, and a pressure roller.

However, this known mechanism has a serious disadvantage. There is always a possibility that the information carrier might slip in respect of the driving shaft, particularly, under severe climatic conditions (moisture, dew, frost, etc.).

The use of driving belts for transmitting rotation from the driving motor to the driving shaft substantially narrows the range of operational temperatures.

The known mechanism cannot be immersed in a liquid, which means that dry friction is always present in the path of the travel of the information carrier, which results in intensive wear of the magnetic heads.

Furthermore, it is a serious disadvantage of the mechanisms of the abovespecified type that they practically cannot be employed with thin metal bands as the information carrier, although these metal bands feature high magnetic and thermal properties, such as their ability to keep the information recorded thereon at temperatures as high as 500°C.

It is an object of the present invention to provide a mechanism which avoids these disadvantages.

The present invention has for its aim the provision of a mechanism for transportation of an information carrier, preferably, of a metal magnetic band, which insures a constant speed of transportation of this information carrier from one spool onto another, and which is reliable in operation, for example, as a component of the emergency and operational systems of the registration of the flight data of aircraft.

This aim is attained in a mechanism for transportation of an information carrier from one spool onto another with the help of a driving motor and means for tensioning said information carrier, in which mechanism, according to the invention, said driving motor is a hydraulic motor having its shaft operatively connected with one of said spools.

It is advisable to include into the hydraulic supply line of said driving motor a metering valve providing for the variation of the rotational speed of said hydraulic motor in accordance with the variation of the amount of said information carrier on one of said spools, said one spool being connected with said metering valve by means of a member responsive to the amount of said information carrier on said spool.

The mechanism for transportation of an information carrier may be enclosed within a hermetically sealed housing filled with liquid.

The present invention will be further described in connection with an embodiment thereof, with reference to the accompanying drawings, wherein:

FIG. 1 is a diagrammatic view which shows schematically a drive mechanism for transportation of an information carrier; and

FIG. 2 is a transverse cross-section of the metering valve of the mechanism shown in FIG. 1 as taken along line 2-2.

Referring now to the appended drawings, the mechanism for transportation of an information carrier, shown in FIG. 1 comprises a hydraulic driving motor 1 and two spools 2 and 3, viz. the take-up spool 2 and the supply spool 3, the output shaft of the driving motor 1 being positively operatively connected by a non-slip connection with the take-up spool 2; means 5 for tensioning the information carrier 4, a metering valve 6, a gauge 7 responsive to the winding radius of the information carrier 4 on the take-up spool 2; the entire mechanism being enclosed within a hermetically sealed liquid-filled housing diagrammatically illustrated in FIG. 1.

The supply spool 3 is operatively connected with the take-up spool 2 through the information carrier 4. Rigidly secured to the shaft of the take-up spool 2 is a first toothed wheel 8 meshing with a second toothed wheel 9 of the external rotor 10 of the means 5 for tensioning the information carrier 4, the toothed wheel 8 also meshing with a third toothed wheel 11 rigidly mounted on the shaft of the driving motor 1.

Rigidly mounted on the shaft of the internal rotor 12 of the means 5 for tensioning the information carrier 4 is a fourth toothed wheel 13 meshing with a fifth toothed wheel 14 rigidly mounted on the shaft of the supply spool 3.

The gauge 7 responsive to the winding radius of the information carrier 4 is in a permanent physical contact with the external turn of the information carrier 4 on the take-up spool 2. The gauge 7 is operatively connected through a shaft 15 and a spring 16 with the rotary valve member 17 (FIG. 2) of the metering valve 6 (FIG. 1). The metering valve 6 communicates through a supply conduit 18 with the driving motor 1 and also communicates through an intake conduit 19 with a source of liquid under pressure, e.g. with a liquid pump (not shown). The metering valve 6 comprises a housing 20 and a rotary valve member 17, the housing having passages 21 for the flow of the working liquid through the metering valve 6.

The herein disclosed information carrier transportation mechanism operates as follows.

When the mechanism is switched into operation, the working liquid from a source of the working liquid under pressure, e.g. from a liquid pump, is supplied through the conduit 19 to the metering valve 6 wherefrom it flows into the driving motor 1 via the supply conduit 18. The driving motor 2 drives the take-up spool 2 in rotation, whereby the information carrier 4 is transported from the supply spool 3 onto the take-up spool 2. The information carrier 4, as it is being unwound from the supply spool 3 and wound onto the take-up spool 2, is tensioned by the information carrier tensioning means 5. As the information carrier 4 is being wound onto the take-up spool 2, the winding radius thereof on the spool 2 increases, and, consequently, it is imperative that the speed of rotation of the take-up spool 2 be varied correspondingly in order for the linear speed of the information carrier 4 to stay constant.

Therefore, as the information carrier 4 is being transported, the gauge 7 of the winding radius of the information carrier 4 on the take-up spool 2 responds to the varying winding diameter and controls the rotation of the valve member 17 (FIG. 2) of the metering valve 6, the movement of the gauge 7 being transmitted to the

rotary valve member 17 through the shaft 15 (FIG. 1) and the spring 16.

As the rotary valve member 17 is turned into different angular positions, the rate of flow of the working liquid to the driving motor 1 through the metering valve 6 is varied.

As a result, the rotational speed of the driving motor 1 is varied accordingly. The adjustment of the rate of flow of the working liquid through the metering valve 6 to the driving motor 1 is defined by the condition that the linear speed of the information carrier 4 should be constant:

$$V = (\pi n) / 30 . R = \text{const.} \quad (1)$$

15

where

V — the linear speed of the information carrier;

n — the angular speed of rotation of the take-up spool (r.p.m.);

R — the winding radius of the information carrier on the take-up spool.

As is known, the rotational speed n of the driving hydraulic motor 1 can be determined from the following formula:

$$n = Q / K^1 \quad (2)$$

where Q is the rate of flow of the working liquid through the hydraulic motor;

K^1 is a permanent factor depending on the geometrical dimensions of the structural parts of the hydraulic motor.

Consequently, it can be seen that

$$V = K \cdot Q \cdot R = \text{const.} \quad (3)$$

where $K = \pi / (30 \cdot K^1)$, is the permanent factor.

Therefore, for the linear speed of the information carrier 4 to be constant, it is imperative that the metering valve 6 should adjust the rate of the flow of the working liquid to the driving motor 1 in reverse proportion to the variation of the radius "R" of the winding of the information carrier 4 on the take-up spool 2 with which the driving motor 1 is operatively connected.

An information carrier transportation mechanism constructed in accordance with the present invention is thus capable of ensuring a constant linear speed of the transportation of an information carrier of any kind (magnetic tape or band, steel wire, thin metal magnetic band, etc.).

The high reliability and the long operational life of the transportation mechanisms constructed in accordance with the invention, together with the fact that these mechanisms can be operated with a metal magnetic band as the information carrier, open for these mechanisms a wide field of applications, for instance, in the construction of emergency and operational registration devices mounted on all kinds of aircraft.

The herein disclosed mechanism for transportation of an information carrier ensures that the information that had been recorded on the information carrier during a flight is preserved under any successive flight conditions, which is particularly essential for the investigation of flight accidents and crashes.

However, a mechanism for transportation of an information carrier, constructed in accordance with the invention, can be used in various branches of industry and technology, as well as domestically.

What is claimed is:

1. A mechanism for the transportation of an information carrier, said mechanism comprising a supply spool on which the information carrier is wound, a take-up spool for receiving the information carrier which is unwound from the supply spool, a hydraulic motor coupled in non-slip driving relation with the take-up spool to unwind the information carrier from the supply spool onto the take-up spool, means for tensioning the information carrier including means drivingly coupling the supply spool and said motor, a fluid pressure source, a metering valve coupled to said hydraulic motor and the pressure source for controlling the flow of fluid to the motor from said pressure source, gauge means for sensing the amount of information carrier

wound on the take-up reel, means coupled to said gauge means and to said metering valve to control the valve for providing a rate of flow of fluid to the hydraulic motor which is related to the amount of information

5 carrier wound on the take-up reel so that the information carrier is driven at a constant linear speed, and a housing enclosing all of the aforedefined elements of said mechanism therein, said housing being hermetically sealed and filled with a liquid.

10 2. A mechanism as claimed in claim 1 wherein said metering valve includes a casing with a passage for flow of pressure fluid from the supply to the hydraulic motor, and a rotary valve member in said casing driven in rotation by the means coupled to the gauge means so as to control the fluid flow in said passage to provide a constant linear speed of travel of the information carrier.
